REFRIGERATOR DOOR CONSTRUCTION

Lawrence A. Philipp, Detroit, Mich., assignor to
Nash-Kelvinator Corporation, Detroit, Mich., a
corporation of Maryland

Application October 24, 1947, Serial No. 781,956

1 Claim. (Cl. 20—35)

1

This invention relates generally to refrigerating apparatus and more particularly to refrigerator cabinet doors.

It is an object of the present invention to provide an improved refrigerator cabinet door construction, reducing heat leakage therethrough into the cabinet.

Another object of the invention is to provide a refrigerator cabinet door of the above mentioned character which is inexpensive to manufacture.

Further objects and advantages of the present invention will be apparent from the following description, reference being had to the accompanying drawings, wherein a preferred form of the present invention is clearly shown.

In the drawings:

Fig. 1 is a front view of a refrigerator cabinet, embodying features of the present invention;

Fig. 2 is a fragmentary, cross sectional view of the cabinet door, taken along the line 2—2 of Fig. 1;

Fig. 3 is a fragmentary, elevational view, partly broken away and in section of the refrigerator door; and

Fig. 4 is a view similar to Fig. 2 of a modification of the invention.

In the drawings, there is shown a refrigerator cabinet, designated generally by the numeral 20. The front of the cabinet 20 is closed by a door 22 which may extend substantially from top to bottom of the cabinet. This door 22 may be hinged, as to 24, to one side of the cabinet. Any suitable type of refrigerating system may be used, such as, the refrigerating system shown in my patent No. 2,361,792, issued October 31, 1944.

The door 22 comprises, in general, an outer or front panel 26 and an inner or rear panel 28. These panels 26, 28 are arranged and attached together, forming a shell in which heat insulation 30 is preferably provided to reduce heat seepage through the door. The door outer panel 26 is made of sheet metal, preferably steel and is dish-like in shape having a top 32, bottom 34 and sides 36. Extending along the rear edges of the door panel 26 is an inturned reinforcing flange 38 preferably having a forwardly directed, bent flange portion 40 for additionally reinforcing the panel 26. The inner panel 28 is a flat metallic sheet which is preferably made of a light weight material, such as aluminum.

In order to reduce heat transfer or heat conduction between the outer panel 26 and the inner panel 28, I make the inner panel 28 of a reduced size with respect to its perimeter; arrange the panel with its outer peripheral edge, as at 41,

2

spaced inwardly of the outer panel flange 38 and connect or attach the panels together by a plurality of spaced apart extensions or clip fasteners 42. To reduce further, conduction or transfer of heat between the door panels 26, 28, the clips 42 are made of a low heat conducting material, preferably stainless steel. A number of these clips 42, widely spaced apart, depending upon the size of the door, suitably attach the panels 26, 28 together with negligible heat conduction therebetween.

A gasket 46 is attached to the outer surface of the flange 38 to seal the joint between the door and front face of the cabinet. This gasket 46 has a seating or attachment base 48 which is held between the door flange 38 and a retainer or clamp 50. The retainer 50 may be an angle member having one leg thereof seating on the seal base 48 and the other leg secured flat against the door panel flange portion 40 by screws 52. Outer end portions of the clips 42 seat on the rear leg of the seal retainer 50 and may be secured to the front panel flange 38 together with the clamp 50 by screws 53. The gasket 46 has a resilient bumper or displaceable portion 54 and an integral, laterally extending lip 55. This gasket 46 overlies and conceals the clips 42 and the spaces between the outer peripheral edge of the rear panel 28 and the flange portion 50 of the door outer panel 26, 50. The clips 42 are bent to form inwardly facing spring sockets 56 on their inner ends to receive outer marginal portions of the inner panel 28. These sockets 56 are covered by the gasket lip 55 which has a downturned inner edge portion 57, engaging the outer surface of the panel 28 just inwardly of the lips. A retainer bead 58 is provided on the inner panel 28, extending along and adjacent the edges of the panel to engage frictionally in the clip sockets 56.

In the modification of Fig. 4, the door comprises in general, a dish-like outer panel 60 and an inner panel 62 which may be like the panels of the above described door. A rubber gasket 64, attached to an inturned flange 66 of the outer panel, has a bumper portion 68 provided with a laterally extending lip 69 which overlaps a marginal portion of the inner panel 62 entirely therearound as in the previously described door. A reinforcing, inturned flange portion 70 of the casing preferably extends entirely around the door and to this flange portion is secured an angle retainer 71 for the rubber gasket 64. One leg of the retainer 71 may be secured to the flange portion 70 by screws 72 or by other suitable securing or attaching means and the other leg of the angle

retainer member seats flat against the outer surface of the seal base, as at 14. As in the previously described door, the inner door panel 62 of the modification has an outer peripheral edge 75 spaced inwardly from the flange portion 70 to decrease heat transfer between the panels. To attach the inner panel 62 to the outer panel 60, I provide a plurality of extension or connecting members 76. These connecting members 76 are spaced along the outer peripheral edge of the inner panel 62 and are attached thereto by fasteners or clips 78. As shown in Fig. 4, the clips 78 are S-shaped presenting oppositely facing sockets for respectively receiving marginal edge portions of the panel 62 and of the connecting members 76. To decrease further conduction of heat between the panels 60, 62 the connecting members 76 are made of a low heat conducting material, such as plastic, and the clips 78 are also preferably made of a low heat conducting metal, such as stainless steel. These clips 78 are also made of a spring or resilient stainless steel so that marginal portions of the panel 62 and the connecting members will be frictionally held thereby in the sockets of the S-shaped clips 78. Preferably, retainer beads 80 and 82 are provided respectively on the panel 62 and on the connecting member 76 to engage in the clip sockets to aid frictionally in attachment of the parts together. Outer end portions of the clip extensions or connecting members 76 seat against the outer leg of the gasket retainer 71 and are attached, together with the gasket retainer 71, to the outer panel flange 66. To this end, the connecting members 76, retainer 71, gasket base 14 and outer panel flange 66 may be provided with aligning apertures to receive spring fasteners 84.

From the foregoing description it will be noted that I have provided an improved refrigerator door construction of a character to decrease heat transfer between outer and inner attached together door panels. By attaching peripherally spaced inner and outer door panels together by bridging or connecting members spaced around the door panels only negligible heat conduction via the narrow, widely spaced connectors is possible. In addition, I have provided a refrigerator

door construction to decrease heat conduction between inner and outer panels and at the same time effect a reduction in manufacturing costs of such doors by decreasing the material used in the making of inner door panels.

Although preferred and modified forms have been illustrated, and described in detail, it will be apparent to those skilled in the art that various other modifications may be made therein without departing from the spirit of the invention or from the scope of the appended claim.

I claim:

A refrigerator cabinet door construction comprising, a door casing having an inturned flange formed with a reinforcing portion bent to extend forwardly, a rear panel spaced rearwardly of said flange having an edge spaced inwardly from said flange reinforcing portion to decrease heat conduction therebetween, a door seal having a base seating on said flange, an angle clamp having one leg seating on said base and the other leg parallel with and secured to said reinforcing portion to secure the seal to the flange a plate having an end portion seating on said leg and an opposite end portion underlying said panel, means attaching said first end portion, leg, base and flange together, resilient means forming a socket on the opposite end portion of said plate to receive an edge portion of said panel, means on said panel within said socket and tensioning the socket forming means, and a rubber extension on said seal having a free side extending over said socket forming means.
